(57) **CLAIM**

The ornamental design for a rain chain component, as shown and described.

DESCRIPTION

FIG. 1 is a top perspective view of the rain chain component; FIG. 2 is a bottom perspective view of the rain chain component;

FIG. 3 is a front elevational view of the rain chain component, the back side having the same design and configuration;

FIG. 4 is a side elevational view of the rain chain component, the opposite side having the same design and configuration;

FIG. 5 is a top view of the rain chain component;

FIG. 6 is a bottom view of the rain chain component; and, FIG. 7 is an upper perspective view of the rain chain component shown in the position of use.

The broken lines represent portions of the rain chain component that form no part of the claimed design. The broken lines in FIG. 7 represent environment and form no part of the claimed design.

1 Claim, 7 Drawing Sheets
